Samuel E. Darby

UNITED STATES PATENT OFFICE.

EDWARD G. BUDD AND JOSEPH LEDWINKA, OF PHILADELPHIA, PENNSYLVANIA, AS-SIGNORS, BY DIRECT AND MESNE ASSIGNMENTS, TO BUDD WHEEL COMPANY, OF PHILADELPHIA, PENNSYLVANIA, A CORPORATION OF PENNSYLVANIA.

HUB STRUCTURE FOR WHEELS.

Application filed September 6, 1916. Serial No. 118,716.

To all whom it may concern:

Be it known that we, EDWARD G. BUDD and JOSEPH LEDWINKA, citizens of the United States, residing at Philadelphia, in the 5 county of Philadelphia, State of Pennsylvania, have made a certain new and useful Invention in Hub Structure for Wheels, of which the following is a specification.

This invention relates to hub structures 10 for wire spoked or other wheels.

The object of the invention is to provide a hub structure for wheels which is simple, economical to manufacture, and efficient in operation.

15 A further object of the invention is to provide a hub structure for wheels which permits the wheel to be readily detachable from its supporting hub, and replaceable thereon, and when replaced upon its hub to be 20 clamped and secured thereon.

A further object of the invention is to provide means for locking the detachable wheel upon its carrying hub, the locking means being released by the application of a spanner or other suitable tool to release the 25 clamping nut.

Other objects of the invention will appear more fully hereinafter.

The invention consists substantially in the 30 construction, combination, location and relative arrangement of parts, all as will be more fully hereinafter set forth, as shown in the accompanying drawings, and finally pointed out in the appended claims.

35 Referring to the accompanying drawings,—

Fig. 1 is a view in central longitudinal section showing a hub structure embodying the principles of our invention, and as applied to a wire spoked wheel.

Fig. 2 is an end elevation of the hub.

Fig. 3 is a broken detail view in section on the line 3, 3, Fig. 1, looking in the direction of the arrows.

45 Fig. 4 is a similar view in section on the line 4, 4, Fig. 1, looking in the direction of the arrows.

Fig. 5 is a similar view on the line 5, 5, Fig. 1, looking in the direction of the arrows.

50 Fig. 6 is a detached broken detail view in top plan of the wedge segments employed to clamp the detachable wheel hub in place.

Fig. 7 is a broken detail view in end eleva-

tion partly in section, showing a means for attaching the wire spokes to the wheel hub.

Fig. 8 is a view in end elevation of the permanent hub member.

Fig. 9 is a view in section on the line 9, 9, Fig. 8, looking in the direction of the arrows.

Fig. 10 is a detail view in section on the line 10, 10, Fig. 1, looking in the direction of the arrows.

Fig. 11 is a broken view in longitudinal section, showing a modified structure embodied within our invention.

The same part is designated by the same reference numeral wherever it occurs throughout the several views.

In structures of vehicle wheels, such as are employed extensively in connection with 70 motor vehicles, and particularly wheels of the wire spoke type, it is desirable to provide means by which the wheel may be readily detachable and removable from its hub, and quickly and easily applied thereto and securely clamped in place in such manner as to be locked in position when applied. It is also desirable to provide means to prevent the accidental disengagement or release of the locking means, by reason of the backing 75 off of the clamping nut usually employed in connection with the locking device, through jolts or otherwise. It is also desirable to provide a hub structure for detachable or demountable wheels, which is simple, economical to manufacture and efficient in operation. It is among the special purposes of our 80 present invention to provide a hub structure for detachable, demountable wheels which secures the advantages and desirable characteristics referred to, and others, in a most 85 simple, economical and efficient manner.

In the drawings we have shown practical 90 embodiments of our invention wherein 11 designates a vehicle axle. This may be 95 either a front steering axle or a rear driving axle, and our invention is not to be restricted or limited in this respect. Suitably mounted upon the axle 11 is a permanent hub member 12. This is in the form of a shell which 100 is journaled upon the axle with, if desired, anti-friction roller bearings 13 interposed.

The hub member 12 is provided with exterior engaging surfaces 14, shown, in this 105 instance, as plane inclined surfaces, upon which is seated correspondingly shaped sur-

faces of the outer hub member 15, thereby forming the driving connection between the hub members 12 and 15. The outer hub member 15 is provided at its inner end with a flange 16, the edge of which is deflected laterally therefrom and formed into portions 17, pressed out of the peripheral plane of said edge portion to afford means for receiving and anchoring the hub ends of the inner spokes 18 in such manner as to enable said spokes to have the proper tangential line or angle of inclination without causing them to be bent when suitably anchored at their other ends in the rim 19. In like manner the outer end of the hub member 15 is formed with portions 20 in its peripheral surface which are pressed out of the peripheral plane of said hub portions to receive and anchor the outer spokes 21, which connect the hub member 15 and rim 19.

The hub member 15 is formed with an outer end wall 22 which constitutes a housing for the nut 23, which nut is threaded onto the outer exteriorly threaded end of hub member 12. Encircling the outer end of hub member 12, and suitably retained thereon are wedge segments 24. These wedge segments may be maintained in assembled relation in any suitable or convenient manner. A simple arrangement is shown wherein in said segments are strung upon an expandible retaining ring 25 which passes through central openings formed through the segments 24. This ring may be retained in position in any convenient manner. A simple arrangement is shown wherein links 26, engage over the retaining ring 25, and are held in place by studs 27, engaging shoulders formed on the inner edges of lugs 28, on the hub member 12. This arrangement affords a flexibility to the wedge members 24, permitting them to be forced radially outward and into bearing contact with an inclined shoulder or surface 29, on the outer hub member 15, to lock the same to the inner hub member 12. The wedge blocks 24 are forced outwardly to accomplish their locking function by the inclined inner surface 30 of the screw caps 23, when the latter is screwed onto the threaded end of the hub member 12.

In order to detach and remove the wheel from the permanent hub member 12, the screw cap 23 is backed off thereby permitting the expandible ring 25, which retains the wedge blocks 24, to contract and thereby causing a release of the engagement of the wedge blocks with the inclined surface 29 of the outer hub member 15. When this is done the hub member 15, and with it the wheel structure, including the spokes and rim, may be readily and easily slipped off from the hub member 12. In like manner in order to replace a wheel upon the hub 12, its hub 15 is slipped over the permanent hub member

12, and the screw cap 23 is then applied and turned up, so that its inclined inner surface 30 engages the wedge blocks 24, and forces them outwardly against the inclined surface 29, the expansion of the retaining ring 25, permitting this, thereby locking the hub member 15, in place.

In the operation of vehicle wheels it sometimes happens that a cap nut 23, by means of which the wheel is retained upon its hub, becomes accidentally backed off through jolts, jars, or the like, thereby releasing the wheel and permitting the latter to leave its carrying hub. To prevent this we propose to employ a suitable lock arrangement for locking the nut in position when sufficiently screwed up to clamp the wheel upon its hub. A simple arrangement of lock is shown in Figs. 1, 3, 4 and 10 consisting of a pawl 31, pivotally mounted between its ends upon a lug 32, carried by the inner end wall of cap 23. One end of pawl 31 is arranged to engage ratchet teeth 33, formed on the outer end of permanent hub member 12.

The other end of pawl 31 is engaged by a stud or button 34, which works through an opening formed centrally through the end wall of cap 23. A spring 35 carried by lug 32, acts upon the button 34, to yieldingly maintain the same pressed outwardly and the other end of pawl 31 pressed into position to engage a ratchet tooth 33. When the cap 23 is screwed onto the end of hub member 12, the pawl 31 rides over the ratchet teeth 33, and engages the said ratchet teeth to prevent the unscrewing of said cap. In order to permit the cap to be unscrewed the button 34 is pressed inwardly thereby releasing the pawl 31 from engaging with the ratchet teeth 33, and then the cap 23 may be unscrewed. Ordinarily the cap 23 is screwed on or off by means of a spanner bar or other convenient tool having prongs which are received in the sockets 36, formed in the outer surface of the cap. By providing the spanner with an additional projection which will enter the opening in which the button 34 operates at the same time the prongs are seated in the sockets 36, it will be seen that the application of the spanner to the nut to turn it up or back it off will automatically release the pawl 31.

In Fig. 11 is illustrated a slightly modified arrangement wherein the wheel is shown applied to a rear or driving axle. In this arrangement the axle 40 is suitably engaged to the inner hub member 41, to drive the same as for example, through the intermeshing portions 42, the outer hub member 43 remaining in essential respects like the hub member 15 above described. In the modification shown in Fig. 11, however, the hub ends of the spokes are secured in blocks 44 which are seated in openings formed through the shell of hub member 43, instead of pressing out

the metal of said shell, as above explained. In the modified arrangement a slightly different retaining means for the screw cap 23 is employed. In this arrangement the end 5 surface of the axle 40 is provided with serrations 45, with which engage cooperating serrations 46, formed in the face of a friction plate 47. This friction plate is held to turn with the screw cap 23, as, for example, by 10 means of lugs 48, and is pressed into frictional engagement with the serrated surface 45 of the axle by means of a spring 49. With this arrangement the backing off of the nut is prevented by the frictional engagement of 15 the serrations 45, 46, which, however, does not substantially interfere with the screwing up of said nut. The advantage of this arrangement is that a special tool is not required to release the retaining means. 20 From the foregoing description it will be seen that we provide an exceedingly simple structure of hub for detachable wheels which offers no serious manufacturing problems or difficulties, and therefore which can be manufactured cheaply and economically. It will 25 also be seen that we provide a structure which permits a wheel to be quickly, readily and easily applied to its carrying hub and locked in place, but which, at the same time, permits 30 quick, ready and easy detachment of the wheel from its hub, and wherein when the wheel is once applied and locked in position it is retained therein without danger of becoming accidentally released.

35 Having now set forth the objects and nature of our invention, and constructions embodying the principles thereof, we wish to be understood that variations and alterations in the details of parts and other arrangements 40 may readily occur to persons skilled in the art and still fall within the spirit and scope of our invention. We do not desire therefore to be limited or restricted to the exact details shown and described. But 45 what we claim as new and useful and of our own invention, and desire to secure by Letters Patent, is—

50 1. In a wheel structure, a permanent hub member having outwardly tapering seating surfaces, a removable hub member having cooperating seating surfaces, at its inner end, and an outwardly flared bearing surface at its outer end, a nut threaded upon the outer end of said permanent hub member and having an inwardly tapered or inclined inner 55 end surface, wedge blocks interposed between said hub members to be engaged by the tapered or inclined surface of the nut, said wedge blocks engaging the outwardly flared bearing surface of the outer hub member to lock said hub member upon the seating surfaces of the permanent hub member, and an 60 expandible ring threaded through said wedge blocks to retain the same in position.

65 2. In a wheel structure, a permanent hub

member having seating surfaces, a removable hub member having co-operating seating surfaces, a nut threaded upon the outer end of said permanent hub member and having an inclined inner end surface, wedge blocks interposed between said hub members to be engaged by said inclined surface, said wedge blocks engaging the outer hub member to lock the same upon said seating surfaces, an expandible retaining ring for said wedge blocks, a lug on the permanent hub member, and means engaging said lug and ring to retain said ring in position.

3. In a wheel structure, a permanent hub member having seating surfaces, a removable hub member having cooperating seating surfaces, a nut for the end of said permanent hub member and having an inclined inner end surface, wedge blocks interposed between said hub members to be engaged by said inclined surface, said wedge blocks engaging the outer hub member to lock the same upon said seating surfaces, an expandible retaining ring engaging said wedge members to retain the same in assembled 90 relation, and retaining links engaging said expandible ring.

4. In a wheel structure, a permanent hub member having seating surfaces, a removable hub member having cooperating seating surfaces, a nut for the end of said permanent hub member and having an inclined inner end surface, wedge blocks interposed between said hub members to be engaged by said inclined surface, said wedge blocks engaging the outer hub member to lock the same upon said seating surfaces, an expandible retaining ring for said wedge blocks, links engaging said retaining ring, and lugs formed on said permanent hub 105 member to hold said links.

5. In a wheel structure, the combination of an inner hub member having a tapered seat of polygonal cross section, an outer hub member having, near its inner end, a co-operating seat of similar cross section and, adjacent its outer end, an outwardly inclined conical surface, a nut threaded on the inner hub member and having a tapered conical nose, a plurality of wedge blocks interposed between the nose of said nut and the conical surface of said outer hub member, and yielding means for retaining said wedge blocks in position.

6. In a wheel structure, the combination of an inner hub member having a tapered seat of polygonal cross section, an outer hub member having near its inner end, a co-operating seat of similar cross-section and, adjacent its outer end, an outwardly inclined conical surface, a nut threaded on the inner hub member and having a conical nose, and an expandible member interposed between said nose and the conical surface on said outer hub member.

7. In a wheel structure, the combination of an inner hub member having a tapered seat of polygonal cross-section, an outer hub member having, near its inner end, a co-operating seat of similar cross-section, an expansible member interposed between said inner and outer hub members, and a nut threaded on one of said members and engaging said expansible member and operable to force the same into locking engagement with said hub members.

8. In a wheel of the class described, the combination of an inner hub, an outer hub removably mounted thereon, means preventing relative rotatative movement of said hubs, a combined hub cap and nut screwed on said inner hub and exerting an axial thrust on said outer hub, the outer face of said nut being flush with the outer end of said outer hub, and a latch carried by and enclosed within said nut and engaging co-operating locking portions on said inner hub.

9. In a wheel of the class described, the

combination of an inner hub, an outer hub removably mounted thereon, means preventing relative rotatative movement of said hubs, said inner hub having a cylindrical outer end screw-threaded and provided with a plurality of ratchet teeth extending parallel to the axis, a nut closing the end of the inner hub screwed on said screw-threaded portion of the inner hub and clamping said outer hub in place, the outer face of said nut being flush with the outer end of said outer hub, and a latch carried by said nut and engaging said ratchet teeth.

In testimony whereof we have hereunto set our hands in the presence of the subscribing witnesses, on this 30th day of August A. D., 1916.

EDWARD G. BUDD.
JOSEPH LEDWINKA.
